UNITED STATES PATENT OFFICE.

CARLOS B. MIRICK, OF WASHINGTON, DISTRICT OF COLUMBIA.

REMOTE CONTROL DEVICE.

Application filed August 24, 1927. Serial No. 215,248.

My invention relates broadly to electrically operated remote control devices and more particularly to remote control devices operated by radio telegraphy.

5 In the remote control devices now in use the principle of the Baudot code is used. This requires the synchronizing of the transmitter and the receiver circuits, so that when the actuating impulses are transmitted at 10 synchronously tuned intervals the receiver will be in a proper condition to select the circuit to be actuated.

The timing of the impulses and the intervals between them have heretofore been 15 governed in the transmitter by the speed of the sending commutator which is normally locked in a given position and released for one revolution whenever a train of signals is sent. The receiver operates in a similar 20 manner and contains a commutator normally locked in a given position and released for one revolution at the same instant as the sending commutator. These commutators are driven by constant speed motors which 25 are adjusted to synchronous speeds and maintained in this condition by governing devices. In these remote control devices the motors must run continuously and be maintained in absolute synchronism or a variance 30 in the circuits controlled will occur.

The object of my invention is to eliminate these motors and to substitute in their place 35 clock mechanisms including a spring driven train of gears with an escapement mechanism that run only during the periods at which the signals are being sent and received, thus effecting great saving in weight and energy. These spring driven mechanisms are so highly developed and well known that they 40 are to be hereinafter referred to as "clock mechanisms" without further detailed description thereof.

Another object of my invention is to incorporate a mechanism for rewinding the 45 driving mechanisms during the period between signals. Since these rewinding mechanisms run but intermittently and need not run synchronously, further gain in simplicity, weight and energy is effected.

50 Further objects of my invention will appear more fully hereinafter as the description of the method and apparatus is developed.

55 My invention consists in the construction, combination and arrangement of parts associated therewith or as will be more fully

hereinafter set forth as shown by the accompanying drawings and finally pointed out in the appended claims.

Reference is to be had to the accompanying drawing showing the embodiment of my invention in which numerals 1, 2 and 3 designate three commutator discs mounted upon a single shaft 4. There is a tendency for the shaft 4 to rotate in a clockwise direction produced by any standard spring and escapement mechanism not shown. This rotation is prevented by a latch 5 which is held against the surface of a cam 6 that is rigidly attached to the disc 2. Adjacent one side of this latch is an electro-magnet 7. The latch 5 is held against the surface of the cam and against the pull exerted thereon by the residuary magnetism in the electromagnet by means of a spring 8. The other end of the shaft 4 is mechanically coupled to the shaft of the rewinding motor 9 which is so wound that, when current passes through the windings of the motor, it will turn the shaft in a counter-clockwise direction.

80 The disc 1 is made of insulating material and has a conductive segment 10 in its periphery. Against the periphery of this disc bear a brush 11 and a plurality of brushes 12. The conductive segment 10 is connected to a slip ring 13 against which bears a brush 14 that forms the other electrical connection to the disc 1.

85 The disc 2 is made of conductive material and has an insulating segment 15 in its periphery. Against the periphery of this disc bears a brush 16. The hub of the disc 2 forms a slip ring against which bears a brush 17 that forms the other electrical connection to the disc 2.

90 The disc 3 is similar to the disc 1 but has only one brush 18 bearing on its periphery to engage the conductive segment 19. This disc has a slip ring 19' against which bears a brush 20 that forms the other electrical contact with the disc 3.

95 The electrical connections of the device constitute four distinct circuits, which are as follows: The master relay and the electromagnetic latch circuit consists of a connection from the source of power 21, through the master relay 22, the brush 14, the slip ring 13, the conducting segment 10, the brush 11, the coil 7 of the electromagnetic latch and to the other terminal of the source of power. 100 The rewinding circuit consists of a connection from the terminal of the source of power 110

21, through the coil 22 of the rewinding relay 25, the contacts 24, the brush 17, the disc 2, the brush 16 and to the other terminal of the source of power. The substitute rewinding 5 relay circuit consists of a connection from the source of power 21, through the coil 22 of the rewinding relay 25, the brush 20, the slip ring 19', the conducting segment 19, the brush 18 to the other terminal of the source of power.

10 The rewinding motor circuit consists of a connection from one of the terminals of the source of power 21 through the contacts 26 of the rewinding relay 25, through the motor 9 and to the other terminal of the source of power.

15 The operation of the device is as follows: At the initial position, that shown in the drawing, three of the circuits are open, but the rewinding relay circuit is closed. There is a continuous flow of current through the 20 coil 22 of the rewinding relay in a closed position.

When the first of a train of signals is received the contacts of the master relay 23 shift from the RS position to the RM position. This causes current to flow from the 25 source of power through the master relay and electromagnetic latch circuit. This flow of current through the coil 7 of the electromagnetic latch effects a movement of the 30 latch 5 away from the cam 6 on the disc 2. The clock mechanism then starts a clockwise rotation of the discs. As the discs rotate the segment 10 first opens the circuit of the electromagnetic latch 35 allowing the latch 5 to become ready for engagement with the cam 6. Then the segment 10 passes under the various brushes 12 for the activation of the different selective mechanisms.

When the discs approach the end of one 40 complete revolution and the train of signals has ceased the contacts of the master relay 23 shift to the RS position and the insulating segment 15 passes under the brush 16, opening the rewinding relay circuit. This permits the contacts 24 of the rewinding relay 45 25 to open and the contacts 26 to close. As the motor 9 rotates the discs in a counter-clock-wise direction the segment 15 passes from under the brush 16. This operation 50 alone however does not reclose the rewinding relay circuit for by the movement of the armature of the rewinding relay 25 the contacts 24 opened the rewinding relay circuit in a second place.

55 When the rewinding motor has rotated the discs in the counterclock-wise direction for an angular movement of slightly less than one revolution the conducting segment 19 passes under the brush 18 and the substitute rewinding relay circuit is closed. This causes a flow 60 of current from the source of power 21, through the coil 22 of the rewinding relay 25 which effects an opening of the contacts 26 and a closing of the contacts 24.

65 When the flow of current through the re-

winding motor 9 has been stopped in this manner, the clock mechanism then tends to rotate the discs in a clockwise direction. Any rotation of the discs in this direction, however, is prevented by the engagement of the 70 latch 5 with the cam 6 of the disc 2. The circuits are then in the initial position above described, from which position the device will operate in a similar manner upon the receipt of another train of signals.

75 It is to be understood that the synchronizing system in the transmitter is identical with that described in this receiver circuit. By the accurate timing possible with the clock mechanism the transmitter and the receiver may 80 be operated without variation.

It will be understood that the above description and accompanying drawings comprehend only the general and preferred embodiment of my invention and that minor detail changes in the construction and arrangement of parts may be made within the scope 85 of the appended claims without sacrificing any of the advantages of my invention.

Having thus described my invention, what 90 I claim is as follows:

1. In remote control devices comprising a transmitter and a receiver, means for synchronizing said transmitter and said receiver, each of said means consisting of a rotatable controller member; a clock mechanism for rotating the said controller member during the transmission of a series of signals, a rewinding motor for rewinding the said clock mechanism, and means upon the controller member 95 for operating the rewinding motor during the periods when the transmitter is inoperative.

2. In remote control devices comprising a transmitter and a receiver, means for synchronizing said transmitter and said receiver, each of said means consisting of a rotatable controller member comprising a plurality of discs, the first and third of which consist of 100 insulating material and carry conductive segments and slip rings and brushes, the second of which consists of conducting material and carries an insulating segment and slip ring and brushes, a plurality of contacts engaged by the first disc for operating the remote control device, a lock engaging the 110 controller member, and means upon the controller member for operating the said lock,

115 a clock mechanism for rotating the said controller member, a rewinding motor for rewinding the said clock mechanism, and a 120 means upon the controller member for operating the rewinding motor.

3. In remote control devices comprising a transmitter and receiver, means for synchronizing said transmitter and said receiver, 125 each of said means consisting of a rotatable controller member, comprising a plurality of discs the first and third of which consist of insulating material and carry conductive segments and slip rings and brushes; the 130

second of which consists of conducting material and carries an insulating segment and slip ring and brushes, a plurality of contacts engaged by the first disc for operating the 5 remote control device, a lock engaging the controller member, and means upon the controller member for operating the said lock, said means consisting of a source of power, an electric circuit from the source of power 10 comprising a master relay, the brush and collector ring of the first disc, the conductive segment and one contact engaged by the first disc, and the lock operating solenoid, a clock mechanism for rotating the said controller member, a rewinding motor for rewinding the said clock mechanism at the end 15 of the motion imparted to the discs by the clock mechanism, and a means upon the controller member for operating the rewinding motor, said means consisting of a source of power, a solenoid operating a relay in the circuit of the rewinding motor, and an electric circuit from the source of power through the said solenoid to the brushes of second 20 and third discs, the second disc operating to close said relay, and the third disc operating to open said relay.

4. In a synchronizing system for remote control devices comprising a transmitter and 30 a receiver and timing devices for the transmitter and the receiver, each of said timing devices consisting of a plurality of discs, a clock mechanism, a rewinding motor for rewinding the clock mechanism and means 35 upon the discs for operating the rewinding motor only when said transmitter is inoperative.

5. In a synchronizing system for remote control devices comprising a transmitter and 40 a receiver and timing devices for the transmitter and the receiver, each of said timing devices consisting of a plurality of discs the first and third of which consist of insulating material and carry conductive segments and 45 collector rings and brushes, the second of which consists of conductive material and carries an insulating segment and a collector ring and brush, a magnetic lock engaging one of the discs, a source of power, an electric circuit for the first disc comprising 50 a brush engaging the conductive segment, an electrical connection through the coil of the magnetic lock, the source of power, a relay and the brush and collector ring of the first disc, a clock mechanism for rotating the discs, a rewinding motor mechanically coupled to the clock mechanism and means 55 engaging the other discs for operating the rewinding motor at the end of the motion imparted to the discs by the clock mechanism.

6. In a synchronizing system for remote control devices comprising a transmitter and a receiver and timing devices for the transmitter and the receiver, each of said timing devices consisting of a plurality of discs, the

first and third of which consist of insulating material and carry conductive segments and collector rings and brushes, the second of which consists of conductive material and carries an insulating segment and a collector ring 70 and brush, a magnetic lock engaging one of the discs, a source of power, an electric circuit for the first disc comprising a brush engaging the conductive segment, an electrical connection through the coil of the magnetic lock, the source of power, a relay and the brush and collector ring of the first disc, a clock mechanism for rotating the discs, a rewinding motor mechanically coupled to the clock mechanism and means 75 engaging the other discs for operating the rewinding motor at the end of the motion imparted to the discs by the clock mechanism, said means consisting of a relay the coils and one set of contacts of which are in series with the source 80 of power and the brushes engaging the second disc, another pair of contacts of said relay in series with the rewinding motor and the source of power.

7. In a synchronizing system for remote control devices comprising a transmitter and a receiver and timing devices for the transmitter and the receiver, each of said timing devices consisting of a plurality of discs, the first and third of which consist of insulating material and carry conductive segments and collector rings and brushes, the second of which consists of conductive material and carries an insulating segment and a collector ring and brush, a magnetic lock engaging 95 one of the discs, a source of power, an electric circuit for the first disc comprising a brush engaging the conductive segment, an electrical connection through the coil of the magnetic lock, the source of power, a relay 100 and the brush and collector ring of the first disc, a clock mechanism for rotating the discs, a rewinding motor mechanically coupled to the clock mechanism and means 105 engaging the other discs for operating the rewinding motor at the end of the motion imparted to the discs by the clock mechanism, said means consisting of a relay, the coils and one set of contacts of which are in series 110 with the source of power and the brushes engaging the second disc, another pair of contacts of said relay in series with the rewinding motor and the source of power and means for shifting the circuit of the rewinding motor.

8. In a synchronizing system for remote control devices comprising a transmitter and a receiver and timing devices for the transmitter and the receiver, each of said timing devices consisting of a plurality of discs, the first and third of which consist of insulating material and carry conductive segments and collector rings and brushes, the second of which consists of conductive material and carries an insulating segment and a collector 120

ring and brush, a magnetic lock engaging one of the discs, a source of power, an electric circuit for the first disc, comprising a brush engaging the conductive segment, an electrical connection through the coil of the magnetic lock, the source of power, a relay and the brush and collector ring of the first disc, a clock mechanism for rotating the discs, a rewinding motor mechanically coupled to the clock mechanism and means engaging the other discs for operating the rewinding motor at the end of the motion imparted to the discs by the clock mechanism, said means con-

sisting of a relay the coils and one set of contacts of which are in series with the source of power and the brushes engaging the second disc, another pair of contacts of said relay in series with the rewinding motor and the source of power, and means for shifting the circuit of the rewinding motor, said means consisting of a brush engaging the third disc and in series with the source of power, the coils of the relay and the brush engaging the collector ring on the third disc. 15 20

CARLOS B. MIRICK.
